UNITED STATES PATENT OFFICE.

FRANK A. WEEKS, OF PLAINFIELD, NEW JERSEY.

DESIGN FOR A MEMORANDUM-PAD CALENDAR.

43,708.

Specification for Design.

Patented Mar. 11, 1913.

Application filed December 26, 1912. Serial No. 738,752. Term of patent 7 years.

To all whom it may concern:

Be it known that I, FRANK A. WEEKS, a citizen of the United States, residing at Plainfield, in the county of Union and State of New Jersey, have invented a new, original, and ornamental Design for a Memorandum-Pad Calendar, of which the following is a specification, reference being had to the accompanying drawings, forming a part thereof, and in which—

Figure 1 is a perspective view, and Fig. 2 a side elevation of a memorandum pad calendar embodying my design.

I claim:

The ornamental design for a memorandum pad calendar, as shown.

FRANK A. WEEKS.

Witnesses:

ARTHUR MARION,
CHARLES C. GILL.
